(57) **CLAIM**

The ornamental design for a binomial die, as shown and described.

DESCRIPTION

FIG. 1 is a left side perspective view of a first embodiment of the new binomial die;

FIG. 2 is a top plan view of the first embodiment thereof;

FIG. 3 is a front view of the first embodiment thereof;

FIG. 4 is a right side elevational view of the first embodiment thereof;

FIG. 5 is a back view of the first embodiment thereof;

FIG. 6 is a left side elevational view of the first embodiment thereof;

FIG. 7 is a bottom plan view of the first embodiment thereof;

FIG. 8 is a left side perspective view of a second embodiment of the new binomial die;

FIG. 9 is a top plan view of the second embodiment thereof;

FIG. 10 is a front view of the second embodiment thereof;

FIG. 11 is a right side elevational view of the second embodiment thereof;

FIG. 12 is a back view of the second embodiment thereof;

FIG. 13 is a left side elevational view of the second embodiment thereof;

FIG. 14 is a bottom plan view of the second embodiment thereof;

FIG. 15 is a left side perspective view of a third embodiment of the new binomial die;

FIG. 16 is a top plan view of the third embodiment thereof;

FIG. 17 is a front view of the third embodiment thereof;

FIG. 18 is a right side elevational view of the third embodiment thereof;

FIG. 19 is a back view of the third embodiment thereof;

FIG. 20 is a left side elevational view of the third embodiment thereof;

FIG. 21 is a bottom plan view of the third embodiment thereof; and,

FIG. 22 is a left side perspective view of the first embodiment, the second embodiment, and the third embodiment of the new binomial die of the present invention.
